UNITED STATES PATENT OFFICE.

NILS P. SJOBRING, OF JAMESTOWN, NEW YORK, ASSIGNOR TO THE AMERICAN METAL DOOR CO., OF JAMESTOWN, NEW YORK, A CORPORATION.

SHEET-METAL DOOR.

No. 926,361.

Specification of Letters Patent.

Patented June 29, 1909.

Application filed February 1, 1908. Serial No. 413,796.

To all whom it may concern:

Be it known that I, NILS P. SJOBRING, a citizen of the United States, residing at Jamestown, in the county of Chautauqua and State of New York, have invented certain new and useful Improvements in Sheet-Metal Doors, of which the following is a specification.

This invention relates to certain new and useful improvements in sheet-metal doors, and the invention consists of the parts and the constructions, arrangements, and combinations of parts which I will hereinafter describe and claim.

An essential object of the present invention is to devise a new and efficient method of securing the rails of sheet-metal doors to the panels; to devise a simple and effective means for securing the glass slab or sheet in doors designed with glass panels, and to provide improved means for securing sheet-metal panels to the rails of doors.

In the accompanying drawings forming part of this specification and in which similar reference characters indicate like parts in the several views:—Figure 1 is a side elevation of a door embodying the salient features of my invention. Fig. 2 is an enlarged longitudinal sectional view of the same, on the line 2—2 of Fig. 1. Fig. 3 is a cross-sectional view, on the line 3—3 of Fig. 1. Fig. 4 is a cross-sectional view, on the line 4—4 of Fig. 1. Fig. 5 is a similar section, on line 5—5 of Fig. 1. Fig. 6 is a cross-sectional view, on a line corresponding to 3—3 of Fig. 1, but showing a modified construction. Fig. 7 is a broken perspective view showing more clearly the means for securing a glass panel. Fig. 8 is a broken perspective view of a portion of a bottom rail showing the manner of securing a sheet-metal panel. Fig. 9 shows a modified means for securing a rail to a metal panel.

The general design of the door shown is well known and follows more or less closely the door disclosed in my former patents 847,443, Mar. 19, 1907 and 809,145, Jan. 2, 1906, in that it may be provided with similar panels on opposite sides, and the side sections or stiles may be integrally formed to present in one body both sides of the doors.

The stiles are substantially identical in construction, and a description of one will suffice for both.

Each of the stiles, S is formed of a single

strip of metal of appropriate shape in cross-section and having a length equal to the desired height of the door, and each stile comprises parallel plates or strips 4 and 5, which are spaced apart a distance equal to the desired thickness of the door from front to rear, the inner edges of these plates or strips being inturned and fashioned with appropriately formed locking-flanges, 6, substantially as shown in my aforesaid former patent.

When constructing the door with a metal panel, as shown in the lower panel of Fig. 1 and in Figs. 2, 4 5, each panel-section, is formed of a sheet-metal plate, p, one for each side of the door, with said plates spaced apart a distance equal to the desired thickness of the panel, and each plate consists of a sheet or strip of suitable length which near one edge is projected or offset, as at 7, and then inclined outwardly in either regular or irregular curve, as at 9, to form a molding portion 70 interior to the inner edge of the side stiles, the free edge of this molding portion being bent inwardly at right-angles to form a wall, 80 10, and thence again bent at right-angles and interlocking with the aforesaid locking flange, 6, formed along the inner side edge of the stile-section, this construction being well shown in my said former patents. The upper and lower rails or end sections of the door 85 may be of identical construction, but when using a glass panel, say in the upper part of the door as in Figs. 1, 2, 3 and 7, the means for securing this panel will be modified, as I 90 will now explain. The said rails or upper and lower end sections of the door each comprise duplicate plates, 15, the outer edges of which are arranged to overlie and rest in engagement with the inturned flanges, 12', 95 formed on the edges of the keeper, 12, to which flanges the said plates, 15, are bolted, riveted, or otherwise securely fastened. The plates, 15, have a length suitable for the desired width of door and the inner edges of 100 said plates are inturned and fashioned with locking-flanges, 16, which substantially correspond to those before described as made on the inner side edges of the stiles.

When it is desired to construct the aforesaid door, or one of equivalent form, with a glass panel, as shown in Figs. 1, 2, and 3, I form the molding portions which surround the panel, of separate pieces, 24 and 25, and it is to these features that my present invention

tion is particularly related. To better distinguish between the separate molding pieces, I will hereinafter refer to the pieces 24 as the fixed molding-pieces and the pieces 25 as the loose molding-pieces although it will be understood that the pieces 25 are loose only in the sense that they are the pieces which are insertible after the glass slab or panel is seated on or against the other pieces and after the fixed pieces are interlocked with the locking-flanges on the stiles and rails, or plates, 15, of the door.

The fixed molding-pieces, 24, have one edge fashioned to interlock with the aforesaid locking flanges, 6, 16 on the stiles and rails, or plates, 15, and they are each bent inwardly and then formed with some appropriate, regular or irregular, curve as shown at 19 to form a molding-portion which terminates in a shoulder at 20. From this shoulder the fixed molding-piece, 24, is bent backwardly to form a wall, 21, which is parallel with the front and rear sides of the door and against which wall the flat side of the glass slab or panel, P, is adapted to seat, as shown, in Fig. 2. At the outer end of the wall, 21, the fixed molding-piece is bent at right-angles, to form an end wall, 22, toward the opposite side of the door, and thence is formed with an inclined wall or portion, 22', out of which or an adjacent part of the said piece, 24, is struck and offset the inclined tongues, 26, of which there may be any desired number. The piece 24 extends beyond this slotted tongue portion and to the side of the door, and has its terminal edge fashioned to interlock with the adjacent locking-flange, 6, of the stile, or 16 of the rail, this depending upon whether the piece 24 described is a part of an end or a side molding for the panel, the construction and arrangement being substantially alike in both cases. The companion molding-piece, namely the loose piece, 25, consists of a sheet of metal which is bent to form a wall, 30, which stands parallel with the wall, 21, of the other piece, 24, the inner edge of said loose piece, 25, being bent at right angles to form a tongue, 31, which lies upon and parallel with the end wall, 22, of the molding-piece, 24, and is designed to slip undersuitable tongues, 32, struck out from the piece, 24, at or near the junction of the wall, 21, thereof with the end wall, 22, as clearly shown in Figs. 2 and 7 thus substantially interlocking one part with the other.

The free end, or edge, of the loose molding-piece, 25, is bent at right angles from the end of the wall, 30, and is thence fashioned with a curved or other molding portion, 33, which may be identical with the corresponding molding portion, 19, on the piece 24; and the terminal free edge of the piece, 25, is formed with an inturned hook-shaped portion 34 adapted to be sprung into engagement with the struck-out inclined tongues,

26, of the fixed molding piece, 24, thereby locking the loose molding piece, 25, to the companion fixed molding piece, 24, and causing the flat surfaces of the glass panels, P, to be firmly clamped between the parallel spaced walls, 21 and 30, of the two molding-pieces, 24 and 25, and presenting a molding finish around the panel of a most attractive character.

In Fig. 6, I illustrate a slight modification of the foregoing construction: In this figure, the fixed molding-piece, 24', is offset at 24^a to form a locking shoulder and the free or outer edge of the loose molding piece, 25', has a hook-shaped portion, 25^a, to interlock with said offset or shoulder. Also, the fixed molding-piece is slightly offset, at 24^b, at the base of the vertical wall of the said fixed molding piece, and the bent portion or tongue, 25^b, of the loose molding piece engages with said offset, as shown in said Fig. 6. In other respects the panel of Fig. 6 is like the one before described for Fig. 2.

As shown in Fig. 2, the lower panel of the door may be composed of metal plates, p, spaced apart and with an intermediate lining of asbestos. These panel plates are secured to the bottom rail by first slitting and then stamping out tongues, 40, beyond the outer face of the panel-plates; and the molding portion of each bottom rail composed of the plates 4—5, has its inner edge bent to form a hook-shaped portion, 41, which is adapted to receive and interlock with the outstanding tongues of the panel-plates, as shown in Fig. 8. By this construction the panel-plates may be shoved into place and their outstanding tongue portions engaged with the hook-shaped portions of the molding portion of the bottom rail and secured thereto without the use of rivets or screws.

In Fig. 9 I disclose a modified means for securing a sheet-metal panel. In this instance the metal sheets forming the panel are slotted or provided with apertures, 42, and the inner edge of the molding-section or piece, which may be integral with a rail, is provided with bent tongues, 43, which enter and interlock with the slots or apertures, 42, in the metal plates of the panel.

From the foregoing it will be seen that I am enabled, by the use of the fixed and loose molding pieces described, to readily insert and secure a glass panel, without the use of screws, rubber-protected channels, or putty.

In operation, the glass is laid in place against the fixed molding-piece, and the companion or loose molding-piece is applied by the inserting of its tongues, 31, under the tongues, 32, at the base of the wall, 21, of the fixed piece, 24, and the free end of said loose molding piece is sprung over, or into engagement with the tongues, 26, of said fixed molding-piece, when the loose piece, 25, is locked to the companion piece and secures

the glass panel in place. By reason of the free or spring-end of the loose molding-piece, said piece is adjustable to any desired thickness of glass. Substantially the same operation is carried out with the modified construction of Fig. 6 for in this case when the glass is inserted, the spring-end of the loose molding-piece is sprung inward and into engagement with the shoulder or offset portion 24° of the fixed molding-piece. In both instances the molding-pieces have portions or walls extending down along the sides of the glass.

Where the metal panel is used, as for instance the lower panel of Fig. 1, the tongues which are struck out of the panel-plates provide a simple and effective means for the engagement of the plates with the bottom rail as the latter may be readily shoved into locking engagement with the outstanding tongues, thus securing the parts without the use of screws, rivets, and like supplemental fastenings.

Among the advantages of the present construction over the prior patented ones, is that by the method shown of fastening the bottom rail to a metal panel by the use of struck tongues, I am permitted to dispense with the use of a separate angle molding, which requires considerable time to make and to apply to a panel. By the present method the molding-portion of the rail is made at one and the same operation with the rail, by the use of appropriate dies, thereby saving material and time and making a construction which may be more easily applied.

The method of securing the glass panel has a distinct advantage over my prior patent inasmuch as the loose molding member is adjustable thereby enabling me to use glass of different thickness, and said member forms a more substantial fastening than that of the former patent. The modifications shown in Fig. 4 is also of advantage because less stock is required and the loose molding-section can be inserted behind the glass with less difficulty also by this arrangement I can hold $\frac{1}{4}$ " glass firmly without the use of putty, screws, cement or rubber protected panels.

Having thus described my invention what I claim as new and desire to secure by Letters Patent is:—

1. In a door or like structure having a glass panel, means for securing said panel, said means comprising opposed molding-members each having a wall to clamp the panel, one of said members having one portion interlocked with the other member and having a second portion sprung into engagement with another portion of said other member.

2. In a door having stiles, rails and a panel, a molding surrounding the panel and comprising pairs of opposed members, one of said members of each pair having its oppo-

site edges locked to an adjacent part of a stile or rail and having an intermediate portion forming a seat for the panel; the other member of the pair being bent to form a seating for the panel and having the portions on each side of the seating interengaged with portions of the companion member of said pair.

3. In a sheet-metal door or like construction having stiles, rails, and a panel, opposed molding-pieces for securing said panel, said pieces comprising a member whose opposite portions are fixed to a door rail or stile, and a member one of whose portions is fitted to the opposing member and whose opposite portion is sprung into locking engagement with said opposing member, said members having parallel opposed surfaces between which the panel is clamped.

4. In a door or the like, the combination with the stiles and rails thereof, of a panel-securing means, said means including opposed molding-pieces each having a wall between which the panel is clamped, one of said pieces having its outer edges fixedly secured to a stile or rail, and the opposing piece having one of its edges fitted to the first-named piece and having its opposite edge sprung into locking engagement with said first-named piece.

5. In a door or the like, the combination with the stiles and rails thereof, of a panel, and a molding surrounding the same, said molding comprising pairs of opposed members at the sides and ends of the panel having opposed walls between which the panel is clamped, one of said members of each pair having its opposite edges fixedly interlocked with the stiles, or rails, at opposite sides of the door, and the other member of the same pair having its inner edge fitted to an intermediate part of the fixed companion member and having its opposite or outer edge sprung into locking engagement with another intermediate portion of said fixed member.

6. In a sheet-metal door, the combination with the stiles and rails thereof each formed with locking flanges, of a panel, and a molding for the same, said molding comprising pairs of opposed pieces one of which, of each pair, has its opposite edges interlocked with the locking-flanges of the stiles or rails at the opposite sides of the door, and has an intermediate wall forming a seat for the panel, the other of said molding-pieces having a wall to bear against the panel and having one edge fitted to an intermediate part of the companion member, and having its opposite edge sprung into locking engagement with another intermediate portion of said companion member.

7. In a sheet-metal door, the combination with parallel spaced plates forming a stile or rail, each of said plates having its edges formed with a locking-flange, of a panel, and

panel-securing means, said means including a molding-section at one side of the panel having one of its edges interlocked with the locking-flange of the plate at one side of the door, and having the opposite portion extended transversely past the panel to the opposite side and interlocked with the locking-flange of the stile or rail plate on that side; and a molding-section at the other side of the panel and opposing the first-named section and between which sections the panel is clamped, said second-named section having one edge fitted to an intermediate part of the first-section and having its outer edge sprung into locking engagement with another intermediate part of the first-named section.

8. In a sheet-metal door or like structure, the combination with parallel plates at opposite sides of the door, said plates having locking-flanges formed on their edges, of a panel, and panel-securing means, said means comprising a molding-section having its opposite edges interlocked with the locking-flanges on the plates at opposite sides of the door, and having its intermediate portion bent to form walls which stand one substantially at right-angles to the other, said intermediate portion of the member having a double series of projecting tongues, one series being near the

junction of said walls and the other series being near one edge of the member; the opposing molding-section having an inner end bent and slipped into engagement with one series of tongues and having an outer edge sprung into engagement with the other series of 35 tongues.

9. In sheet-metal door and like construction, a sheet-metal molding comprising two opposed sections having vertical parallel spaced walls adapted to receive a panel therebetween, one of said sections having locking-flanges, at its opposite edges, and having struck out tongues near the base of its vertical wall, said section having other tongues struck out from a portion near one edge, and 45 inclined; and the other section having its inner edge bent to slip under the first-named tongues and having its outer edge substantially hook-shaped and adapted to be sprung into locking engagement with the second- 50 named series of tongues.

In testimony whereof I affix my signature in presence of two witnesses.

NILS P. SJOBRING.
